(57) **CLAIM**

The ornamental design for a refrigerant hose accessory, as shown and described.

DESCRIPTION

FIG. 1 is a front elevational view of a refrigerant hose accessory showing our new design with a refrigerant hose attached thereto as shown in broken lines.

FIG. 2 is a perspective view thereof.

FIG. 3 is a perspective view thereof.

FIG. 4 is a front elevational view thereof, the rear elevational view being a mirror image thereof.

FIG. 5 is a left side elevational view thereof.

FIG. 6 is a right side elevational view thereof.

FIG. 7 is a top plan view thereof; and,

FIG. 8 is a bottom plan view thereof.

The broken lines of FIG. 1 are for illustrative purposes only and form no part of the claimed design.
